(57) **CLAIM**

The ornamental design for silicone card frame flip with RFID payment device, as shown and described.

DESCRIPTION

FIG. 1 is a front view of the RFID payment device used in the silicone card frame clip;

FIG. 2 is a plan view of the RFID payment device used in the silicone card frame clip with the device top material removed to expose chip and antenna circuits internal to RFID payment device;

FIG. 3 is a reduced, front view of the silicone card frame clip with RFID payment device;

FIG. 4 is an exploded, perspective view thereof;

FIG. 5 is a reduced scale, environmental view thereof; and,
FIG. 6 is an exploded, opposite side perspective view thereof.

The broken line showing is for illustrative purposes only and forms no part of the claimed design.

The RFID payment device is shown detached for clarity of illustration.
